UNITED STATES PATENT OFFICE.

CARL BENSON, OF YOUMAN, COLORADO.

SICKLE HANGER.

Application filed February 14, 1922. Serial No. 536,571.

To all whom it may concern:

Be it known that I, CARL BENSON, a citizen of the United States, residing at Youman, in the county of Gunnison and State 5 of Colorado, have invented a new and useful Sickle Hanger, of which the following is a specification.

The objects of my invention are to produce a device in which the sickle of a mowing- 10 machine can be sharpened more easily and quickly than by any existing machine or method. This is accomplished by means of an arrangement in which the weight of the sickle is balanced by an equal weight, there- 15 by making it possible to sharpen the sickle by merely guiding it over the grind stone.

Also that the sickle can be held in any angle or direction, so that the cutting edge of each tooth can be applied to the face of the 20 grind-stone. This arrangement is particularly adapted to the requirements of the farmer doing the work alone. I attain this object by means of the device illustrated in the accompanying drawing in which:

25 The figure is a side elevation.

The legs or standards 1, and the rail 2 secured to the legs constitute the frame work.

A cable or rope 5 is provided at its two ends with suitable holders 7, adapted to connect to the ends of a sickle bar, said cable or rope drawn thru two double pulleys 3 and a pulley 4 attached to a weight 6. The double pulleys 3 are movable on the rail 2, said rail is bent upwards at its ends to prevent the pulleys from running off. The weight 30 6 is sufficient to counter-balance the weight 35 of the sickle-bar.

By means of this arrangement the sickle bar may be easily raised or lowered to the 40 desired position for grinding, and any portion of the sickle bar can be applied directly to the face of the grind-stone.

Having described my invention I claim:

In a sickle-hanger, the combination of an 45 overhead rail, separate double pulleys free on the rail, a sickle holding cable on the pulleys, a counter-weight suspended on the cable, between the double pulleys, the said weight to counter-balance the weight of the sickle; the said double-pulleys being free to 50 move on a railing, substantially as shown and described.

CARL BENSON.
